(57) **CLAIM**

The ornamental design for a photo display assembly, as shown and described.

DESCRIPTION

FIG. 1 is a front perspective view of the photo display assembly of the present invention;

FIG. 2 is a front elevational view of the photo display assembly shown in FIG. 1;

FIG. 3 is a rear elevational view of the photo display assembly shown in FIG. 1;

FIG. 4 is a left side elevational view of the invention shown in FIG. 1;

FIG. 5 is a right side elevational view of the invention shown in FIG. 1;

FIG. 6 is a top plan view of the invention shown in FIG. 1; and,

FIG. 7 is a bottom plan view of the invention shown in FIG. 1.

Shading lines are included in various views to depict that the panes in the photo display are transparent.

1 Claim, 5 Drawing Sheets
